UNITED STATES PATENT OFFICE.

ELIHU THOMSON, OF LYNN, MASSACHUSETTS, ASSIGNOR TO THE THOMSON-HOUSTON ELECTRIC COMPANY, OF CONNECTICUT.

ELECTRIC RAILWAY.

SPECIFICATION forming part of Letters Patent No. 470,221, dated March 8, 1892.

Application filed October 9, 1889. Serial No. 326,491. (No model.)

To all whom it may concern:

Be it known that I, ELIHU THOMSON, a citizen of the United States, and a resident of Lynn, in the county of Essex and State of Massachusetts, have invented a certain new and useful System of Electric Traction and Power Haulage, of which the following is a specification.

My invention relates to means for maintaining electrical connection between a moving object—such as a car or other vehicle—and a stationary electric source—such as an electric line—connected with a generator and extending parallel to the path of movement of such object.

My invention consists, first, in the combination, with an elongated contact bar or plate elongated in the direction of movement of the vehicle, of a series of projecting line-contacts pivoted to swing either forward or backward in the direction of movement of the vehicle and each normally out of connection with the line and separated from one another by spaces approximately equal to the length 25 of the contact bar or plate, but a little less than such length, and electric switches actuated by a part moving with the vehicle so as to place the projecting contacts in connection with the line in succession as they are engaged by the elongated contact bar or plate.

My invention consists, further, in a special means and combination for effecting this connection and in other details of the system to be hereinafter described and claimed.

The projecting contacts, which in the case of a horizontally-moving object are dependent from suitable supports, are preferably pendulous or pivoted so as to swing in the arc of a circle.

Other features of the invention will be referred to in detail in connection with the accompanying drawings.

My invention is particularly applicable to use in mines where it is desired to use electric railways and to supply the motors from a main-line conductor placed close to the top or side of the galleries. In such case my invention affords a means whereby the line may be kept continually insulated and protected from accidental contacts or short circuits to which it would be particularly liable, owing to its sit-

uation and to the presence of moisture and consequent leakage.

In the accompanying drawings, Figure 1 is a side elevation of a line, a car, and devices embodying my invention. Fig. 2 is a plan of the contact mounted on the car. Fig. 3 is a side view of the pendent contact enlarged. Figs. 4, 5, 6, and 7 show modified constructions of the projecting contact.

In Fig. 1, C is a car or vehicle propelled electrically by the motor M, carried or otherwise connected with the driving-axles of the wheels D. S is a long metallic plate, bar, or strip with its ends turned down and which may be made in the form of a trough or curved piece having a length somewhat greater than the total length of the vehicle. In fact, it may be as long as convenient; but when curves exist it will be found necessary to shorten its length somewhat and to correspondingly increase the width. This strip, bar, or plate, elongated in the direction of its movement, is the contact through which connection is made from the line or source to the circuit on the vehicle. L is an insulated wire strung on suitable supports or in any way run along the track. At intervals along said wire or conductor, a little less than the efficient length of the contacts S on top of the vehicle, are placed contact-making devices consisting of projecting contacts P, which bear upon or touch the conducting-strip S when the vehicle brings that strip along or alongside thereto. These projecting contacts are suitably hung or supported in any desired way, but are normally out of connection with the line. This may be accomplished by providing for them suitable supports of insulating material. In order to form electric connection between the line and the contact bar, plate, or strip S, I provide suitable electric switches, which are mechanically actuated by engagement of some device or part carried by the vehicle with a part connected to or carrying the switch.

For convenience I utilize the projecting contacts themselves as the carriers of the electric-switch contact and mount such projecting contacts, so that when they are moved by engagement of the elongated contact bar or strip S with them the electric-switch contacts will be closed, and thus establish the elec-

trical connection. The projecting contacts engaged by the bar may be mounted for this purpose in any desired manner. In Fig. 1 they are pendulous and are provided with 5 suitable circuit-closing or switch contacts p , which come into connection with contacts $z z$, electrically connected to line by attachment thereto or in any other way connected to the source through suitable conductors, 10 when the contacts P are swung to one side of their normal position. When this connection is made and the contact S is also in engagement with the contact P , the circuit from the line or source to the vehicle-circuit is completed. 15 This vehicle-circuit may contain the usual variable resistance V in the circuit to the motor and return-conductor or may contain any other apparatus. The vehicle may also be provided with the usual reversing- 20 gear or current-reversing arrangements for changing the direction of motion. The track T may be made the medium of return of the current by contact with the wheels of the car, one end of the motor-circuit being attached 25 to the axles. Any generator G which furnishes the current to the line L and track T by its terminals may be used to furnish the power for driving the vehicle. It will now be seen that as the vehicle progresses it will 30 touch in succession the pendent contacts P and close their connection with the line L at the points provided, at which moment the current will be fed into the strip S and to the motor for the propulsion of the vehicle. It 35 will also be seen that the line L is at very few points exposed to leakage of current and that it is not required that it run in a straight line between the pendants, but may curve or otherwise be diverted to get around obstacles. 40 It may, in fact, run along the side of the gallery instead of the roof, with branching connections to the pendants. The contacts P themselves may be placed anywhere convenient, even on the side, and the strip S also be 45 placed in accordance with the position of the contacts.

The conducting-strip S is shown in Fig. 2 as having edges $e e$ lateral to it and upturned with flaring ends where curved down. This 50 trough shape is for the purpose of better contacting with the contact-brushes or contact ends of the contacts P and bringing them into position, especially where the pendent contacts have lateral play, as well as a backward 55 and forward play. The strip S might of course consist of a simple wire and the contacts P P^2 be provided with grooved rollers running on the same, as indicated in Fig. 6. The contacts might, as before intimated, 60 consist of simple contact-brushes secured to and carried by the line L , while the strip S would be simply a flat plate of sufficient width coming into connection with the contact-brushes, as shown in Fig. 7. The spaces between the 65 contact brushes or pendants P P^2 on curves would be less—that is, they would not be separated by so great an interval—and the

contact-strip S , if a flat plate on top of the vehicle, would not contact first and last on the ends of the vehicle, but on the side toward the center as the brushes swept over it. 70

In Fig. 3 the pendulous projecting contact itself is seen more clearly as terminating at the lower end in a wire brush and as having lateral ears or projections $p p$, which contact 75 with the pieces $Z Z$, carried by or attached to the wire L when the pendant is thrown out of vertical by the movement of the vehicle under it. Suitable springs may be employed also for holding the pendant in its middle 80 position, thus assisting the action of gravity and, if strong enough, preventing them from moving by contact of the bodies of men with them. The pendants, as seen in Fig. 1, may be supported from insulators I , inserted into the 85 rock in case of mining, thus giving a firm support to the pendants and, in fact, making a support also for the line when so desired. It is sometimes desirable that the depending contact itself be insulated by a covering of insulating material, and that the terminal contact-brush B at the contact end be also covered from 90 contact, except with the contact of the vehicle, which is intended to engage with it. Thus in Fig. 4 L is the line, P is the pendent contact covered all over with an insulator, while B is the exposed brush at the lower end, normally covered by a conical cap or shield K , forced down by a spring X when the strip S is drawn away by the motion of the vehicle, thus covering 95 the brush B until the approach of the strip S , which lifts the conical cap K and exposes the end of the brush for contact with said strip. 100

In Fig. 5 a modified form of line-contact is shown. The rod P^2 enters a socket or tubular support N , made, preferably, of insulating material, while P^2 is of conducting material and terminates in a roller R , which makes contact with the plate or wire S , carried by the vehicle. At Z^2 is a switch-contact space, 110 which is open when the part S is not engaged with the roller R ; but on the lifting of the roller R by the movement of the vehicle the switching-contacts at Z^2 are closed, so as to feed current from the line L to the roller R 115 for the operation of the vehicle. Many minor details operating in the same way and sub-serving the same purpose could be designed, as will be well understood by most engineers. 120

It is obvious that my invention is as well applicable to two sets of lines and contacts for a double line as to the case where the return-circuit is made by the rails instead of by the additional line. 125

What I claim as my invention is—

1. The combination, with an electric line, of a series of pivoted contacts normally out of electrical connection therewith and each pivoted to swing either forward or backward in the direction of movement of the vehicle, a contact bar, plate, or strip carried by a vehicle and of a length slightly greater than the distance between the successive projecting contacts and adapted to engage with them in 130

succession, and electric switches the contacts of which are mounted on suitable supports, which are engaged by a part moving with the vehicle and are thereby moved positively into 5 circuit-closing position, so as to establish electrical connection between the line and the series of projecting contacts as the elongated contact bar or plate makes connection with the said projecting contacts.

10 2. The combination, with a vehicle or carrier, of a contact bar, plate, or strip moving therewith and elongated in the direction of movement, a series of swinging projecting line-contacts, each pivoted to swing in the 15 direction of movement of the vehicle either forward or backward and separated by spaces approximately equal to the effective conducting length of said contact plate, bar, or strip and respectively normally insulated from the 20 electric line, and electric switches normally open and having contacts carried by the movable projecting contacts, as described, for establishing connection between the line and the projecting contacts in succession through 25 the positive movement of the latter in either direction, produced by engagement of the elongated bar or strip carried by the vehicle.

3. The combination, with the electric line, of a series of pendent movable contacts normally out of connection therewith and each hung above the way on a suitable pivot or hinge arranged to permit the pendent contact to swing in a plane parallel to the movement of the vehicle in either direction, an elongated 35 contact bar or strip carried by a movable support and adapted to make connection with said contacts in succession, and circuit-closers carried by said movable contacts and adapted to make connection between the same 40 and the electric line when the contacts are moved in either direction by engagement of the elongated bar or strip.

4. The combination, with the series of pivoted line-contacts normally insulated from the electric line or source and adapted to 45 swing either forward or backward in the direction of movement of the vehicle, of the elongated movable contact moving in connection with said pivoted contacts, and switch-contacts mounted on opposite sides of said 50 pivoted contacts for completing the connection between the electric line and said pivoted contacts when the latter are swung either forward or backward.

5. The combination, with the elongated 55 movable contact, of the series of normally insulated pivoted contacts, each hung as a pendulous contact arm or lever adapted to swing in both directions from normal in a direction parallel to the line of track, an electric line, and circuit-closers carried by said 60 pivoted contacts at front and rear for making connection with the line when said contacts are swung out of normal position.

6. The combination, with the series of contacts normally insulated from the line of the protective insulating-caps extending down over the contact ends, as and for the purpose 65 described.

7. The combination, with the line-contact, 70 of the movable shield normally covering the lower or contact-making end.

8. The combination, with the series of projecting line-contacts, of the horizontal contact strip or plate carried by the vehicle and 75 having upturned sides and turned-down ends.

Signed at Lynn, in the county of Essex and State of Massachusetts, this 4th day of October, A. D. 1889.

ELIHU THOMSON.
